CLAIM

The ornamental design for a shaping body suit as shown and described.

DESCRIPTION

FIG. 1 is a front perspective view of a shaping body suit showing our new design;

FIG. 2 is a front view thereof;

FIG. 3 is a rear view thereof;

FIG. 4 is a left side view thereof;

FIG. 5 is a right side view thereof; and,

FIG. 6 is a rear perspective view thereof.

The broken line showing of a body in the figures shows environment which forms no part of the claim. The broken lines that cross the claimed surfaces of the shaping body suit represent stitching, which does form part of the claimed design.
